US00D720754S

(12) **United States Design Patent**
Chin et al.

(10) **Patent No.:** US D720,754 S
(45) **Date of Patent:** ** Jan. 6, 2015

(54) **IMAGING DEVICE**

(71) Applicant: **Hewlett-Packard Development Company**, Houston, TX (US)

(72) Inventors: **Chung Chiet Edwin Chin**, Singapore (SG); **De-Ming Xu**, Shanghai (CN); **Wen-Cong Huang**, Shanghai (CN); **Chuan-Gang Luo**, Shanghai (CN)

(73) Assignee: **Hewlett-Packard Development Company, L.P.**, Houston, TX (US)

(**) Term: **14 Years**

(21) Appl. No.: **29/444,506**

(22) Filed: **Jan. 31, 2013**

(51) LOC (10) Cl. **14-02**

(52) U.S. Cl.

USPC **D14/422**

(58) **Field of Classification Search**

USPC D14/420, 422, 425, 462–470, 424, 389, D14/125, 399; D18/54, 55, 50, 53, 36–39, D18/14, 18–21, 49, 46, 52, 56, 51, 54.4; D13/164, 168; 358/400, 401, 448, 474, 358/486–488, 496, 497, 494, 473, 302, 468, 358/498; 382/312, 317, 321, 315; 400/613, 400/613.1–613.4, 690.1–690.4, 691–694, 400/88, 175; 399/107, 379, 380, 211, 212; 235/462.11, 462.41, 472.01, 470, 235/462.43; 361/680, 681; 378/177, 187, 378/188; 101/93.4, 269; 355/78; D24/165, D24/169, 186; 600/502, 503, 499, 494, 490, 600/485, 500, 492, 480, 493, 495, 479; 128/900; 16/286; 347/104, 109, 5; 271/186, 225, 126, 121, 137, 138

See application file for complete search history.

Primary Examiner — Susan Moon Lee

CLAIM

The ornamental design for an imaging device, as shown and described.

DESCRIPTION

FIG. 1 is a first front perspective view of an imaging device; FIG. 2 is a second front perspective view thereof; FIG. 3 is a front elevation view thereof; FIG. 4 is a rear elevation view thereof; FIG. 5 is a first side elevation view thereof; FIG. 6 is a second side elevation view thereof; FIG. 7 is a top plan view thereof; and, FIG. 8 is a bottom plan view thereof. Broken lines and unshaded portions contained within broken lines are not claimed.

1 Claim, 8 Drawing Sheets
